A. T. GOSSOM

LINGERIE CLASP

Original Filed Sept. 14, 1923

Fig. 5 Alvina T. Gossom Inventor

By Jesse R. Stone

Attorney

UNITED STATES PATENT OFFICE.

ALVINA T. GOSSOM, OF ST. LOUIS, MISSOURI.

LINGERIE CLASP.

Application filed September 14, 1923, Serial No. 662,648. Renewed January 31, 1925.

To all whom it may concern:

Be it known that I, ALVINA T. GOSSOM, a citizen of the United States, residing at St. Louis, St. Louis County, Missouri, have 5 invented a certain new and useful Improvement in Lingerie Clasps, of which the following is a full, clear, and exact description, such as will enable others skilled in the art to which it appertains to make and use the same.

10 My invention relates to clasps for securing the shoulder straps of lingerie to the outer garment of the wearer to prevent the said straps from slipping off the shoulder.

It is a common difficulty in the ordinary 15 types of underwear now in use to have the shoulder straps continually slipping off the shoulders of the wearer, and it is an object of my invention to provide an adjustable attaching means which may be secured to the 20 outer garment of the wearer and support the straps of the undergarments in such manner that the said straps will remain in proper position.

Another object is to provide a supporting 25 means of this kind which may be secured detachably to the outer garment so that it may be used with different dresses and serve in each case to support the shoulder straps of the under garment.

Referring to the drawing herewith, wherein like numerals of reference are applied to like parts in all the views, Fig. 1 is a side elevation of a pin, which may be employed in connection with my invention; Fig. 2 is 30 a plan view of a strip of fabric, preferably elastic fabric, employed in connection with the pin shown in Fig. 1; Fig. 3 is a side elevation of said fabric strip; Fig. 4 is a transverse section showing the fabric strip secured to the pin, said pin being cut approximately on the line 4-4 of Fig. 1, and Fig. 5 is a perspective view illustrating the 35 use of this attachment upon the clothing of the wearer.

The invention may be readily understood by referring to the drawing. I contemplate employing a safety pin, which may be of ordinary type, or preferably may be made as is the ordinary safety pin, but having 40 the back portion 1 of the pin bent for-

wardly at 2 and 3 to thus provide a central portion 4 which may be secured to a strip of fabric 5. By thus forming the back portion of the pin, the fabric is secured against movement laterally along the pin, and thus 55 will hold it more securely. The strip of fabric shown at 5 may be made of any material, preferably elastic, and strong and light so as to take up as little space as possible. I form on one half of the fabric two 60 metallic eyelets, 6, to receive the snaps 7 upon the opposite half of the strip, these parts being arranged so that when the strip is folded in the middle the eyelets and snaps 65 will register in such manner as to snap together, as shown in Fig. 4. In doing this, the central portion 4 of the safety pin is included within the central fold of the fabric, as shown in the drawing.

In the use of this device, the fabric is 70 folded over the central portion of the pin and the first snap adjacent the fold is engaged so as to hold the strip upon the pin. The pin is then secured on the shoulder of the outer garment 8, on the inner side thereof, as shown in Fig. 5. The outer portion 75 of the fabric is then clasped around the strap or straps of the undergarment, and when the said straps are thus included, the outer snap 7 is secured together so as to prevent 80 the removal of the shoulder straps from this support.

It will be noted that the clasp may be secured to the garment in a very inconspicuous manner and will not show at all under 85 ordinary conditions. The device is light in structure, and will not interfere with the movements of the wearer, and will prevent the straps of the wearer's lingerie from slipping off the shoulder. It will be easily attached or detached, and will be simple in 90 construction. The further objects and advantages of this device will be apparent without further description.

I claim:-

1. A lingerie clasp comprising a safety pin, a strip of flexible material adapted to fold midway of its ends to include the back portion of said pin, releasable means to secure said flexible strip to said pin, and means 100

to secure the ends of said strip together to include a strap of clothing in the manner described.

2. A lingerie clasp comprising a safety pin having a pin portion and a back portion, a flexible strip of material adapted to fold midway of its length to include said back portion, means to prevent lateral move-

ment of said strip on said back portion and a snap at the ends of said strip to secure 10 said ends together to include a shoulder strap in the manner described.

In testimony whereof, I hereunto affix my signature this the 31 day of August, A. D. 1923.

ALVINA T. GOSSOM.
